UNITED STATES PATENT OFFICE.

SIMON W. FARBER, OF BROOKLYN, NEW YORK.

DESIGN FOR A CASSEROLE HOLDER.

Application filed March 20, 1929. Serial No. 30,536. Term of patent 14 years.

To all whom it may concern:

Be it known that I, SIMON W. FARBER, a citizen of the United States of America, residing at Brooklyn, in the county of Kings, city and State of New York, have invented a new, original, and ornamental Design for Casserole Holder, of which the following is a specification, reference being had to the accompanying drawing, forming a part thereof.

The drawing shows a perspective view of the article showing my new design.

I claim:

The ornamental design for a casserole holder substantially as shown.

SIMON W. FARBER.
